UNITED STATES PATENT OFFICE.

ADOLF W. PRESSLER, OF KEENE, NEW HAMPSHIRE.

DESIGN FOR AN ADVERTISING SIGN.

Application filed June 27, 1922. Serial No. 2,836. Term of patent 14 years.

To all whom it may concern:

Be it known that I, ADOLF W. PRESSLER, a citizen of the United States, residing at Keene, in the county of Cheshire, State of New Hampshire, have invented certain new, original, and ornamental Design for Advertising Sign, of which the following is a description, reference being had to the accompanying drawing, forming a part thereof.

Figure 1 is a front view;
Fig. 2 is a sectional view, showing my new design.

I claim:
The ornamental design for an advertising sign, as shown.

In testimony whereof, I affix my signature.

ADOLF W. PRESSLER.
